UNITED STATES PATENT OFFICE.

JOSEPH ARMSTRONG, OF WOBURN, MASSACHUSETTS.

IMPROVEMENT IN THE TREATMENT OF HIDES AND SKINS.

Specification forming part of Letters Patent No. 22,925, dated February 15, 1859.

To all whom it may concern:

Be it known that I, JOSEPH ARMSTRONG, of Woburn, in the county of Middlesex and State of Massachusetts, have invented a new and useful Improvement in the Process of Pressing Hides and Skins Preparatory to Stuffing them with Grease; and I do hereby declare that the same is fully described in the following specification.

My invention is an improvement on the improvement in currying leather for which Letters Patent of the United States of America, numbered 16,573, were granted to me on the 10th day of February, A. D. 1857. My invention so patented consisted in employing a press, as stated in the specification, previous to and in connection with the application of the oil or grease by a peg-lined cylinder or other equivalent means, the press serving to remove the tan-liquor from and compact the hide, the peg-lined cylinder subsequently restoring or plumping the hide and impregnating it with grease. In carrying out the said invention as patented the hides were taken from the tan-vat, and while they were in a wet state were put into a powerful press, like a cotton or cider press, and there subjected to pressure to such extent as to expel from them much, if not all, the moisture or liquid contained in them.

I have found that although a press will operate to excellent advantage in freeing a pack of hides from most of the liquor, yet, as the direction of the pressure is nearly vertical, much of the liquor will remain in the hides along or near to and in their outer edges, and whether the hides be pressed in a box or between a bed and platen only. Owing to the irregular shape of the outer edge of a hide, it is impossible to bring its entire outer edge into contact with the sides of a press-box when such is used, and even when the edges are overlapped by other hides they still retain the moisture and require to be exposed more or less to either heat or atmospheric desiccation to prepare them for the stuffing part of the process.

In order to facilitate the expression of the tan-liquor, or prevent it from collecting and remaining in the edges of the hides, and expel it uniformly from all parts of the hide during the process of pressing the hide, I pack in contact with each edge or part of the hide in which

liquor would be likely to remain dry scraps of hide or cotton waste, or any other suitable material which will absorb the liquor during the pressing process and abstract it from such edges and parts. I have found this addition to the pressing process to be of very great advantage.

In preparing a mass of hides for being compressed, I usually place the hides in a box or frame made without any bottom or top, such frame being supposed to be deposited on the bed of the press. During the process of laying one hide upon another I closely ram or pack against its edges and between the same and the inner surface of the frame, or against such parts of it as may be necessary, the absorbent material. This I carry on during the process of filling the frame, and after the frame has been sufficiently supplied with hides it may be raised upward on the mass so as to allow more hides to be laid in the heap and packed with the absorbent matters. After the heap has been made of the required thickness the press should be put in operation so as to compress the mass. On removal of the hides they will be found to have the tan-liquor uniformly expelled from them, the edges being as dry as the other parts of them. In this way the process of treating the hide or preparing it for being stuffed with grease is very much facilitated.

What I claim is—

The above-described improvement on my hereinbefore-mentioned patented process of treating hides, or, in other words, I claim, in combination with the application and use of a press in connection with the impregnation of the hide with grease by a peg-lined cylinder or any equivalent means, the employment of scraps of hide or other suitable absorbents in the press and against the edges and other necessary parts of the hides, and so as during the operation of the press to absorb the liquor from such edge or parts on or in which it would be likely to remain, as specified.

In testimony whereof I have hereunto set my signature this 1st day of September, A. D. 1857.

JOSEPH ARMSTRONG.
